UNITED STATES PATENT OFFICE.

GEORGE L. ABBOTT, OF CORNING, NEW YORK, ASSIGNOR OF ONE-HALF TO
CHARLES F. HOUGHTON, OF SAME PLACE.

BOTTLE-STOPPER LOCK.

SPECIFICATION forming part of Letters Patent No. 588,211, dated August 17, 1897.

Application filed January 27, 1897. Serial No. 620,969. (No model.)

To all whom it may concern:

Be it known that I, GEORGE L. ABBOTT, of Corning, county of Steuben, and State of New York, have invented a new and useful Improvement in Bottle-Stopper Locks, of which the following is a specification.

The object of my invention is to provide an effectual and simple lock or seal for bottle-stoppers; and the invention consists in the peculiar construction and arrangement of the neck of the bottle and its stopper to receive a locking-pin, as more fully described hereinafter.

The invention also consists in the details of construction and combination of parts hereinafter described and claimed.

In the accompanying drawings, Figure 1 is a vertical longitudinal section through a bottle having my invention applied thereto in its preferred form. Fig. 2 is a bottom plan view of the stopper removed.

Referring to the drawings, A represents a jar provided with the usual neck *a*, and B represents a stopper fitting snugly in the neck and provided with an interior main chamber *b*. The neck is formed, preferably at diametrically opposite points, with holes *C*, which register with corresponding openings *D*, formed in the wall of the stopper at diametrically opposite points. A locking pin or bolt *E* is extended through the holes in the neck and stopper and serves to prevent the stopper from being removed without first removing the bolt. At one end the bolt is provided with a head *e* and its opposite end is formed with an opening to receive a lock *f*. Other means for locking the bolt in place may obviously be employed, but I prefer to adopt that shown as being that most convenient where it is necessary to frequently remove the stopper.

In order to prevent the contents of the jar

from coming in contact with the locking-bolt in cases like the present, where the stopper is chambered, I propose to inclose the locking-bolt, which is effected by connecting the 45 openings in the stopper by means of a tube *G*, having its end seated and firmly secured in the openings. This tube forms in effect a secondary chamber in the stopper independent of the main chamber and extending 50 through the same. In addition to its function in preventing the contents of the jar from coming in contact with the locking-bolt this secondary chamber effectually prevents the contents escaping through the openings in the 55 stopper and the neck to the outside.

Having thus described my invention, what I claim is—

1. The combination with a bottle having its neck provided with openings, of a stopper provided with a main chamber and with a secondary chamber extending through the main chamber and registering with the openings in the neck of the bottle and a locking-pin extending through the opening in the neck 65 and through the secondary chamber in the stopper.

2. The combination with the bottle having its neck formed with openings, of a stopper provided with a main chamber and with openings, a tube having its ends seated and secured in the openings in the stopper and a locking-bolt extending through the openings in the neck of the bottle and through the tube. 70

In testimony whereof I hereunto set my 75 hand, this 25th day of January, 1897, in the presence of two attesting witnesses.

GEORGE L. ABBOTT.
